AUTOMATIC LIGHTING ATTACHMENT FOR ELECTRIC ALARM CLOCKS

Filed Dec. 1, 1951

Gustav Stein INVENTOR

BY Harry F. A. Metzler

ATTORNEY.

UNITED STATES PATENT OFFICE

2,636,336

AUTOMATIC LIGHTING ATTACHMENT FOR
ELECTRIC ALARM CLOCKS

Gustav Stein, New York, N. Y.

Application December 1, 1951, Serial No. 259,371

3 Claims. (Cl. 58—19)

1

The present invention relates to improvements in electric alarm clocks and, more specifically to a new and improved attachment for electric alarm clocks for automatically closing an electric circuit.

One object of the present invention is the provision of a device of the character described which will close automatically an electric circuit for a lighting device or the like at the beginning of the alarm of the clock and for opening and re-closing the circuit at the will of the operator independently from the alarm mechanism, so that a person who is awakened by the alarm at an early hour does not have to fumble around in the dark searching for a light switch but will have light in his room as well as at the dial of the alarm clock until he moves a lever on the clock for switching off the light.

Another object of the present invention is the provision of a device of the character described which has a source of light, such as an electric light bulb directly attached to the alarm clock in such a manner that the main portion of the bulb will illuminate the room while a small portion thereof will illuminate the dial of the alarm clock.

A further object of the present invention is the provision of a device of the character described which can be installed easily and quickly by any watchmaker or amateur mechanic into existing electric alarm clocks, although it can be made also as standard equipment for newly manufactured clocks, and which consists primarily of plastic material and a minimum of metal parts.

Still another object of the present invention is the provision of a device of the character described which is simple in construction, consisting of only a few inexpensive parts which can be assembled easily and quickly, so that this device can be manufactured and sold at a low price, but which is also sturdy, durable and well adapted for the purpose for which it is intended.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

In the accompanying drawing a preferred form of the invention has been shown.

2

In said drawing:

Figure 1 is a fractional front view of a preferred embodiment of my invention as it appears when installed in an electric alarm clock with the back cover removed from the clock housing;

Fig. 2 is a sectional view on the line 2—2 of Fig. 1; and

Fig. 3 is a wiring diagram.

Similar reference characters refer to similar parts throughout the several views.

In the drawing the numeral 2 denotes a clock housing which has in its top wall an opening 4, and in a side wall a slot 6. Within the housing 2 there is any ordinary, well-known electrical clock and alarm mechanism having a solenoid 8, a core 10, a lever 12 which swings downwardly when the alarm begins to sound, a shiftable cam bar 14 for shutting off the alarm by raising the lever 12, as well as a dial 13. A cable 14 with a plug 16 is provided for connecting the clock to an electric current outlet (not shown). The above mentioned parts form no part of my present invention.

The attachment according to my invention consists of the following: A lever 18, which preferably is made of non-conductive plastic material or the like has a handle portion 20 (Fig. 1), which extends partially through the slot 6, a cam portion 22, and a hub portion 24 which is connected by an arm portion 26 to the handle portion 20. A pair of recesses 28 and 30 are provided at the upper end of the arm portion, and a conductive member 32 attached to the hub and arm portions of the lever 18 terminates at one end into the recess 28. A conductive bearing bracket 34, to which the lever 18 is pivoted at 36, is secured to an insulating base 38 by means of screws 40 or the like. The base 38 is secured to any suitable part of the inner side of the housing 2 by means of screws 42 or the like. If the housing 2 is made of insulating material, the bracket 34 can be secured thereto directly. A cylindrical member 44, whose axis preferably is parallel to the axis of the pivot 36, is secured to a rod 46, which is attached to the lever 12 by means of soldering or by any other suitable means. The member 44 is located and arranged in such a manner that it will engage the cam portion 22 and move the lever 18 from the position shown in full lines in Figure 1 to the position indicated in dash-and-dotted lines in Fig. 1 as soon as the lever 12 swings downwardly at the beginning of the sounding of the alarm of the clock.

A resilient conductive arm 48 engages with

one end one of the recesses 28 or 30 while its other end is secured to an insulating member 50 by means of screws 52 or the like. The member 50 is secured to any suitable stationary part of the clock mechanism or the like. A socket 54 is attached to the inner side of the housing 2 by means of clamps 56 or the like in such a manner that its upper edge is in spaced relation to the inner side of the housing 2. An electric light bulb 58 is inserted into the socket 54 and protrudes through the opening 4 partially beyond the outer side and partially beyond the inner side of the housing 2, so that it can illuminate not only the room but also the dial 13, which is either in spaced relation to the inner side of the housing 2 or is transparent.

If the lever 18 is in the position shown in full lines, the outer end of the arm 48 rests in the recess 30 of the insulating lever 18, so that the electric circuit for the bulb 58 is interrupted. If the parts 12, 44 and 46 swing downwardly, at the beginning of the sounding of the alarm, the member 44 causes the lever 18 to swing in a clockwise direction into the position indicated in dash-and-dotted lines, so that the outer end of the arm 48 engages the recess 28 and touches the conductive member 32, thus closing the bulb circuit, so that an electric current will flow from the terminal 60 of the cable 14 through a wire 62, the bulb 58, a wire 64, the arm 48, the member 32, the bracket 34, and a wire 66 to the second terminal 68 of the cable 14. Due to the shape of the cam portion 22 as shown in Fig. 1, the parts 12, 44 and 46 can be raised back to their position shown in full lines by pushing the bar 16 for shutting off the alarm without changing the position of the lever 18. Thus the alarm can be shut off without switching off the light bulb 58, so that the operator can use the lever 18 as a switch for switching on or off the bulb 58 without changing the position of the bar 16.

The wires 64 and 66 can be directly connected to the cable 14, or they can be connected to a pair of conductive rails 70 and 72, which may be secured to an insulating plate 74 by means of screws 76 or the like; and the plate 74 can be secured to the housing 2 by means of screws 78 or the like. If the housing 2 is made of insulating material, the plate 74 can be omitted and the rails 70 and 72 can be secured directly to the housing 2.

Since certain changes may be made in the above article and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which as a matter of language might be said to fall therebetween.

Having thus fully described my said invention, what I claim as new and desire to secure by Letters Patent is:

1. In an electric alarm clock which has electrically operated alarm means and an electric light bulb mounted on the clock and protruding partially beyond the outer side of the clock and partially into the clock, an automatic lighting attachment comprising a lever having a cam portion and a handle portion as well as a pair of recesses and a hub portion, a conductive mem-

ber attached to said lever and terminating with one end at the hub portion and with its other end at one of said recesses of said handle, a conductive bearing bracket to which said lever is pivoted being mounted within an electric alarm clock, means for engaging the cam portion of said lever being mounted on the alarm means of the alarm clock, an insulating member mounted within the alarm clock, and a resilient conductive arm engaging with one end one of the recesses of said lever and having its other end secured to said insulating member, one terminal of said light bulb being conductively connected to said resilient arm while its other terminal is connected to the first terminal of a source of current providing electricity for the alarm clock, and said bearing bracket being conductively connected to the second terminal of said source of current, so that the electric circuit of said light bulb is closed if said lever is moved by said means for engaging the cam portion into a position in which said resilient arm engages that recess of the lever into which terminates one end of said conductive member, and that said circuit is interrupted if said lever is in a position in which said arm engages said other recess.

2. An automatic light attachment for electric alarm clocks comprising a lever of insulating material having a cam portion and a handle portion as well as a pair of recesses and a hub portion intermediate said handle portion and said cam portion, a conductive member attached to said lever and terminating with one end at the hub portion and with its other end at one of said recesses of said handle, a conductive bearing bracket to which said lever is pivoted being mounted within an electric alarm clock, a cylindrical member whose axis is parallel to the axis around which said lever is movable being adapted for engaging the cam portion of said lever and secured to the alarm means of the alarm clock, an insulating member mounted within the alarm clock, a resilient conductive arm engaging with one end one of the recesses of said lever and having its other end secured to said insulating member, an electric illuminating device on said alarm clock, and a wire connecting said bearing bracket to the first terminal of a source of current providing electricity for the alarm clock, one terminal of said illuminating device being conductively connected to said resilient arm while its other terminal is connected to the second terminal of said source of current, so that the electric circuit of said illuminating device is closed if said lever is moved by said cylindrical member into a position in which said resilient arm engages that recess of the lever into which terminates one end of said conductive member, and that said circuit is interrupted if said lever is in a position in which said arm engages said other recess.

3. In an electric alarm clock which has a housing as well as a dial in spaced relation to the inner side of said housing and an electric alarm clock mechanism provided with alarm releasing means within the housing as well as an electric light bulb protruding partially beyond the outer as well as the inner side of a portion of said housing, a lever of insulating material having a handle portion partially extending beyond the outer side of said housing a cam portion as well as a pair of recesses and a hub portion intermediate said handle portion and said cam portion, a conductive member attached

to said lever and terminating with one end at the hub portion and with its other end at one of said recesses of said handle, a conductive bearing bracket to which said lever is pivoted being mounted within said housing, a cylindrical member whose axis is parallel to the axis around which said lever is movable being adapted for engaging the cam portion of said lever and secured to the alarm means of the alarm clock, an insulating member mounted within the alarm clock, and a resilient conductive arm engaging with one end one of the recesses of said lever and having its other end secured to said insulating member, one terminal of said light bulb being conductively connected to said resilient arm while its other terminal is connected to the first terminal of a source of current providing electricity for the alarm clock, and said bearing

5 bracket being conductively connected to the second terminal of said source of current, so that the electric circuit of said light bulb is closed if said lever is moved by said cylindrical member into a position in which said resilient arm engages that recess of the lever into which terminates one end of said conductive member, and that said circuit is interrupted if said lever is in a position in which said arm engages said other recess.

10 GUSTAV STEIN.
